UNITED STATES PATENT OFFICE.

JOHN MANNING VAN HEUSEN, OF JAMAICA PLAIN, MASSACHUSETTS.

COLLAR.

1,352,563.

Specification of Letters Patent. Patented Sept. 14, 1920.

Application filed January 22, 1916. Serial No. 73,526.

To all whom it may concern.

Be it known that I, JOHN MANNING VAN HEUSEN, a citizen of the United States, residing at Jamaica Plain, Suffolk county, 5 State of Massachusetts, have invented certain new and useful Improvements in Collars; and I do hereby declare the following to be a full, clear, and exact description of the invention, such as will enable others 10 skilled in the art to which it appertains to make and use the same.

This invention relates to turned-down collars of seamless fabric, and particularly to 15 collars of multiply fabric which is sufficiently stiff to maintain the shape of the collar without the employment of starch, while nevertheless sufficiently pliable to assume the necessary curvature to fit the neck of the wearer without undue rigidity. In 20 making turned-down collars from seamless fabric, and particularly from multiply fabric of the nature referred to, it is important that the collar should be so constructed that it will fit and set properly upon the 25 neck-band of the shirt and around the neck of the wearer. Where there is no line of division between the outer turned-down portion and the neck-band portion of the collar, or even where such a natural line of 30 fold is provided, as by the omission of several threads from one or more of the plies of a multiply fabric with resulting formation of a weakened fold portion of increased flexibility, the folding of the fabric along 35 a straight fold results in a tendency of the inner neck-band portion to be gathered or puckered, with respect to the outer turned-down portion. If a collar of this nature is worn, it has been found that it will not fit 40 properly around the neck of the wearer, even where the collar fits tightly around the neck-band of the shirt, unless special provision is made in the design and construction of the collar.

45 This disadvantage can be overcome by making a natural curve in the fabric and by weaving the outer turned-down portion longer than the inner portion. This method of constructing collars, however, forms no 50 part of the present invention, which has to do more particularly with fabrics of a uniform nature throughout, or fabrics which have a natural line of fold provided 55 therein and which are otherwise of a uniform construction.

Where the line of fold is a straight line,

provision is made for lengthening or shortening the inner neck-band portion in order that, on the one hand, the lower part of the neck-band may be permitted to be lengthened or stretched to adapt itself to the neck-band of the shirt, while the upper part of the collar adapts itself to the neck of the wearer and, on the other hand, to provide against the tendency to gather or pucker, 60 where the inner neck-band and the outer turned-down portion would otherwise be of substantially the same length and possess this tendency.

Where the line of fold of the collar is 70 curved to a greater or less extent in order that the inner neck-band portion may be shorter than the outer turned-down portion, and in order that more room may be left for the neck-tie, the folding of the collar from a flat piece of fabric results in 75 shortening of the lower edge of the neck-band and lengthening of the lower edge of the turned-down portion. According to the present invention, provision is made for 80 lengthening the inner neck-band portion, and particularly the lower part thereof, in order that it may properly fit around the neck-band of the collar, and, at the same time, assume the necessary position for the 85 comfort of the wearer, and for proper appearance.

The invention comprises, generally, the provision, in or as a part of the neck-band portion of the collar, of means for lengthening or shortening the neck-band, and particularly the lower portion thereof which has to be mounted upon the neck-band of the shirt, in order that the collar may properly 90 adjust itself to the neck-band, and in order 95 that it may present the proper appearance, and assume the proper position, upon the neck of the wearer.

The invention will be further described in connection with the embodiments thereof 100 illustrated on the accompanying drawings, in which—

Figure 1 represents a collar of the turned-down type, embodying the invention;

Fig. 2 shows the collar of Fig. 1 unfolded; 105

Fig. 3 is an enlarged view, with parts broken away, of one of the gussets of Figs. 1 and 2;

Fig. 4 is a sectional view of one of the 110 gussets;

Fig. 5 represents a modified embodiment of the invention; and

Fig. 6 is a vertical sectional view of the central portion of the collar of Fig. 2.

The collars illustrated are made up, generally, of the usual neck-band portion 1, and 5 of the turned-down or folding portion 2 of seamless fabric having a weakened portion at the fold as indicated at 8 in Fig. 6. Tabs or tongues 3, of the usual construction, are provided at the ends of the neck-band portion, and have therein buttonholes 4, also of the usual construction.

In order to provide for the lengthening or shortening of the neck-band portion, as the case may be, suitable means is provided 15 therein or is made a part thereof, for permitting this lengthening or shortening. Such means, according to the present invention, takes the form of notches or grooves or indentations, preferably of V shape, 20 which are provided with gussets closing the same and permitting or effecting the desired expansion or contraction of the neck band to the desired extent, and thereby permitting the neck band to be lengthened or 25 shortened and thereby adjusted to the neck band of the shirt. These notches are, in the preferred embodiment of the invention, closed with an elastic fabric which will permit the desired elongation, or which will 30 effect the desired shortening, while nevertheless presenting a yielding element or elements which will make the collar fit closely around the neck band of the shirt.

The V-shaped notches and gussets may be 35 one or more in number, and may be differently arranged. In some cases they may be provided at both sides of the back buttonhole or near the front buttonholes, or symmetrically distributed therebetween. In 40 other cases, they may be provided at the back buttonhole of the neck-band, and the buttonhole may be in the elastic material of the gusset, thereby providing for a reinforced buttonhole when desired, and, at the

same time, for the desired yielding, and 45 lengthening or shortening.

In Fig. 2 the neck-band is shown as provided with V-shaped gussets 5, between the front and rear buttonholes, while in Figs. 1, 2 and 5 the gusset, of elastic material, is 50 shown at 6 at the back of the collar, surrounding the back buttonhole which is made therein. The curved portion of the lower edge of the collar-band is indicated in Fig. 5. A suitable construction of one of the 55 gussets is shown in detail in Figs. 3 and 4.

From the above description it will be noted that the invention is capable of many different embodiments other than those specifically illustrated and described. The accompanying claims are accordingly intended to have a corresponding comprehensive interpretation.

What I claim is:

1. A soft turned-down collar of multiply 65 interwoven fabric having a straight fold portion of increased flexibility therein and provided in its inner or neck band portion with one or more indentations having gussets secured thereto and closing the same, 70 substantially as described.

2. A soft turned-down collar of multiply 75 interwoven fabric having a straight fold portion of increased flexibility therein and provided in its inner or neck band portion with an indentation at the back thereof, said indentation having a gusset closing the same, and a buttonhole made in said gusset, substantially as described.

3. A soft turned down collar of multiply 80 interwoven fabric provided in its inner or neck-band portion with one or more indentations, said indentations being provided with elastic material permitting lengthening and shortening thereof, substantially as 85 described.

In testimony whereof I affix my signature.
JOHN MANNING VAN HEUSEN.
